TYPEWRITING MACHINE

Filed July 27, 1922

Fig. 1.

UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed July 27, 1922. Serial No. 577,799.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

The present invention relates to tools or 10 devices for locking certain parts of a typewriting machine while a type-block is being set and soldered upon a type-bar. More particularly, the invention is for use in connection with a typewriting machine of the 15 rotary-platen class, in which the type-bars, each carrying a type-block having a plurality of characters thereon, are pivoted on a segment, to be swung to the platen, and in which the platen is on a frame shiftable 20 up and down between case-positions.

It is important that the type-blocks be originally so positioned on the type-bars as to print in proper alignment, and it is likewise equally important that, when a type 25 gets out of alignment, or is to be replaced, because injured or because a different character is desired, the repositioning or replacement may be effected expeditiously by the workman, with accuracy, and with a minimum of trouble. In the placing or replacing 30 of a type-block upon a type-bar, an anvil, or type-block-support, and adjusting means therefor, have heretofore been mounted on the platen-shaft; and the type-bar has been swung to the type-block on such anvil 35 or support, and soldered to the type-block after the latter has been brought to true position by adjustments of the anvil. In this operation, no shifting of the platen-frame, 40 and consequent displacement of the anvil, should take place.

An object of the present invention is the provision of a tool or device, insertable into the machine, to lock the platen-frame in a 45 fixed case-position, preferably lower-case-position; which tool or device may be of cheap and simple construction, expeditiously and conveniently, and without adjustments of any sort, be placed, removed and 50 locked in position. In the preferred form of the invention, this tool consists of a rela-

tively stiff strip of spring-metal, shaped to engage and lock together the main frame and the platen-frame of the machine.

In machines of the character mentioned, 55 the type-bars, upon depression of the type-keys, are swung to the platen, around pivots on a type-segment, and are returned to a type-rest by means of springs. When, therefore, in the placement or replacement of a 60 type-block, a type-bar is swung to the anvil on the platen-shaft, it should be fixedly held there, against the action of its return-spring until the solder has hardened, if risk of displacement of the block on the type-bar is 65 to be avoided.

An object of the invention is the provision of means for holding the type-bar to the type-block on the anvil, preferably with a spring-pressure, in such manner as to pre- 70 clude all possibility of disturbance of the type-block on the bar after the block is in true position. A feature of the invention is a tool for this purpose, which, like the tool for locking the platen-frame in case- 75 position, may be cheap and simple, and be placed, removed and held in position without adjustments, with a minimum of trouble, and which may consist simply of a relatively stiff strip of spring-metal. 80

Other features and advantages will hereinafter appear.

In the accompanying drawings.

Figure 1 is a view, in side elevation, partly cross-sectional, of a typewriting machine, 85 showing the parts of the present invention in place therein, and also showing the type-anvil and adjusting devices therefor in place on the platen-shaft for the soldering operation. 90

Figure 2 is a front view, partly cross-sectional, of one end of the machine, showing the tool in place, by means of which the platen-frame is locked against shifting during the type setting and soldering operations. 95

Figure 3 is a perspective view of the tool which holds the type-bar for the setting and soldering operations.

The machine, to which the invention is 100 applied, is a front-strike machine, comprising a main frame 10 and a frame 11, shiftable

with the platen 12 between case-positions. The case-shifting mechanism forms no part of the present invention and is not shown. The platen is revolubly mounted on an axis 13. The carriage, which has letter-feed and return movements on the shift-frame, comprises side plates 14 and cross-pieces 15 and 16. Rollers 17 on the carriage, at the rear thereof, ride upon a rail 18 on the upper end of a plate 19 which forms the rear of the shift-frame. The cross-piece 16 of the carriage forms a rail riding on ball-bearings 20, supported on a rail 21, secured by screws 22 to brackets 23, attached by screws 24 to the shift-frame 11. Side plates 25 of the shift-frame are pivotally connected at 26 to links 27, one at each side of the machine, which links 27 are pivotally connected at 28 to the main frame 10 at the rear of the machine. For further supporting and guiding the shift-frame on the main frame, arms 29, fast to a rock-shaft 30, journaled at each end in the side of the main frame, have, at their forward ends, pins 31, which are received in recesses or bifurcations 32 in the lower edges of the side plates 25 of the shift-frame. Stops, in the form of screws 33, adjustably set by means of lock-nuts 34 on brackets 35, one at each side of the machine, determine the normal or lower-case position of the shift-frame, upon contact of the screws 33 with flanges 33^a, one on the lower edge of each of the side plates 25 of the shift-frame. The brackets 35 are secured to a cross-piece 36, which connects the side plates of the main frame. For determining the upper-case-position of the shift-frame, there are stop-arms 37, secured to the cross-piece 36, one at each side of the machine, which arms have lateral offsets at their upper ends to carry stop-screws 38, adjustably set in the arms 37 by means of lock-nuts 39. When the shift-frame is thrown up, the flanges 33^a thereon are engaged by the stop-screws 38, and the shift-frame is thus arrested in upper-case-position. The parts thus far described are not new with the present invention.

One feature of the present invention is a tool for locking the shift-frame 11 against shifting movement on the main frame 10 preliminary to and during the operations of setting and soldering the type. As shown in Figure 2, this tool consists of a relatively stiff steel spring, folded upon itself at 40 and 41, and having the ends 43 and 44 thereof turned toward each other, so that, when the ends 43 and 44 are inserted between the side plate 45 of the main frame and the corresponding side plate 46 of the shift-frame, the legs 47 and 48 of the tool will be compressed toward one another, to permit placement of the tool. When the tool is in position, as shown in Figure 2, the spring-action thereof causes the legs 47 and

48 to lie flatly against and press upon the frame-members 45 and 46, respectively. The side piece 45 of the main frame has, at its upper edge, a laterally-inturned bead 49, under which, in positioning the tool, a shoulder 50, formed by a turn in the tool, snaps, and which thus holds the tool down in place against accidental upward displacement. The curvature of the turn 50 in the tool, however, causes the legs 47 and 48 thereof to be cammed together, to permit withdrawal of the tool when the same is pulled up by means of the loop 40, which forms a handle therefor. In the formation of the loop 41 in the tool, the same has a bend 51 therein, which, when the tool is in place, overlies the upper edge of the corresponding side piece 25 of the shift-frame. Since the tool is held down by the bead 49 of the main frame, the bend 51 of the tool holds the shift-frame down in lower-case-position, against the stops 33, as shown in Figure 2. The platen-axle, to which the anvil-supports are attached, in the operations of setting and soldering the type, is thus assured of a constant position as to its elevation during such setting and soldering operations.

An anvil and adjusting devices, in connection with which the invention may be employed, are shown in Figure 1. In the use of such an anvil and adjusting devices, the platen is temporarily removed from its axle to allow for the mounting of the anvil, and also preferably to allow for the positioning of a short, dummy or temporary platen for testing the alignment and setting of the type. The dummy-platen and anvil-supports are carried by a metal tubing 52, having heads or bushings, through which the platen-axle 13 passes, and which are secured to the platen-axle by set-screws or other means (not shown). Preferably, the dummy-platen or tube 52 carries a toothed wheel (not shown), engageable by a spring-detent (not shown), for holding the axle 13 against rotary movement during the adjusting and testing operations. The dummy-platen being short, the anvil may be mounted in a central position upon the tube 52, but, in any event, by proper movement of the carriage, the anvil may be brought to printing position.

As shown in Figure 1, the anvil-supports comprise a bracket 53, journaled for angular adjustment on the tube 52, and carrying a set-screw 54, for locking the same to the tube 52 in any desired angular position thereon. The bracket 53 comprises two pairs of ears 55; adjustably set between the ears of each of which pairs is one of two ears 56, offset rearward from, and forming part of, a second bracket 57. The ears 56 are slotted to receive a bolt 58, which is also passed through all of the ears 55 on the bracket 53,

and which at its end is in threaded engagement with one of the ears 55. The ears 55 are slightly flexible, so that, when the bolt 58 is tightened, the ears 56 on the bracket 57 are clamped and the bracket 57 thus held against movement. When the bolt 58 is loosened, the bracket 57 may be moved forward and backward, or swung angularly, with respect to the bracket 53.

10 The bracket 57 comprises a flat plate 59, against which a flat plate 60, forming the platform of the anvil, is set. The anvil 60 has an ear 61 offset rearward from the upper end thereof through a vertical slot 62 in the plate 59 of the bracket 57. The bracket 57 also has an ear 63 offset rearward from the upper edge thereof; and on which the anvil is adjustably supported by means of a thumb-screw 64. The screw 64 is 20 threaded through the ear 63 of the bracket 57, and below the ear 63 is grooved at 65, to fit within a bifurcation in the ear 61 of the anvil. By turning the knurled head 66 of the screw 64, the anvil is adjusted upward 25 and downward on the bracket 57. For holding the anvil flat against the plate 59 of the bracket 57, the latter has secured thereto, by screws 67, a pair of metal strips which overlie the side edges of the anvil, and thus 30 serve as ways, in which the anvil may be adjusted. The anvil, at the lower edge thereof, has a forwardly-projecting lip or offset 68 to form a ledge for aligning and determining the position of the base of the type 35 to be soldered to the type-bar.

In operation, the proper position and all 40 adjustments of the anvil are first determined by means of a type and type-bar other than the one on which the setting and soldering operations are to be performed. After the anvil and brackets therefor, just described, have been set upon the tube 52 at the printing position, any type-bar may be swung, by depression of its type-key, to the anvil.

45 While the bolt 58 is loose, the bracket 57 may be turned angularly until the type-piece rests flat on the anvil-platform; and may be adjusted forward and backward to the proper setting for printing. Thereupon the bolt 58 is tightened. The screw 64 is then 50 turned to move the anvil up until the ledge 68 thereof is in engagement with the base of the type. The correct position of the anvil being thus determined, the type used 55 in ascertaining such position is released, and the type-bar, on which a type is to be set and soldered, is then thrown to the anvil. The type-bars, at their ends, are set in a well-known manner in slots or grooves in 60 the rear faces of the type-pieces. The type-piece is set with its face flat against the platform of the anvil, and with its base flat on the anvil-ledge 68. The bar is then inserted and soldered in the groove in the type. It 65 is in connection with this setting and solder-

ing operation that another feature of the invention is concerned.

This other feature of the invention is the means for holding the type-bar forward, against the mechanism which normally returns the same to its rest. The type-bars 69 are pivotally mounted in a well-known manner upon a rod 69^a, carried by a type-segment 70. Draw-rods (not shown), connect to ears 71 on the type-bars, and to the type-key-levers (not shown), so that, when the type-key is depressed, the bar swings up to Figure 1 position.

70 Springs (not shown) return the type-bars to normal position unless the same are held. It is desirable here, however, that there be no such return movement of the type-bar until after the solder has set; but, on the contrary, that the type-bar be firmly held with the type 69^b flat against the anvil-platform during the setting of the solder, and, further, in order that the workman may properly position the type thereon and apply the solder without the necessity of at 75 the same time holding the type-bar.

80 A tool for this latter purpose is shown in perspective in Figure 3, and is shown in operative position in Figure 1. It consists of a relatively stiff spring, having three legs 72, 73 and 74. The legs 72 and 73 serve to hold the tool in place, and the leg 74 serves to hold the type-bar. The legs 72 and 73 are offset from one another by a bend 75 in the spring, so that the spring may be compressed to permit the foot or heel 76 of the 85 leg 72 to be set under and against a bead 77 on the upper edge of the front plate 78 of the main frame, and so that the heel or foot 79 of the leg 73 may be set under and against the segment 70. If the type-bar has been 90 swung forward previous to the insertion of the tool, then, when the latter is positioned as just described, a finger 80, offset laterally from the end of the leg 74 of the tool, will bear with a spring-pressure upon the rear 95 edge of the type-bar, holding the same firmly in position, with the type flat against the anvil-platform. The tool may be removed by simply catching the same under the bend 75 of the finger and pulling the 100 same up and out of the machine.

105 Certain features herein disclosed are the invention of Joseph Lindburg and are claimed in his application, Serial No. 501,021, filed September 16, 1921; the claims 110 in this case being limited to features not disclosed in said Lindburg application.

115 Variations may be resorted to within the scope of the invention, and portions of the improvements may be used without others.

120 Having thus described my invention, I claim:

1. A device, insertable into a typewriting machine, having means thereon for interengaging the main frame of the machine, and 125

means thereon for engaging over the platen-shift-frame of the machine, to hold the latter frame against raising movement.

2. A device, insertable into a typewriting machine, consisting of a spring having means thereon for positively engaging within the main frame of the machine, and means thereon for engaging over the platen-shift-frame of the machine, to hold said frames against relative vertical movement.

3. A device, insertable into a typewriting machine, consisting of a spring having two legs, bent to produce a bowed handle element and being compressible toward each other, for entry between the main frame and the platen-shift-frame of the machine, one leg being adapted to positively engage within the main frame, and the other leg being adapted to engage over the platen-shift-frame, to hold the latter against vertical movement when the device is in place.

4. A device, insertable into a typewriting machine, consisting of a spring having two legs, compressible toward each other, for entry between the main frame and the platen-shift-frame of the machine, one leg being adapted to engage the main frame, and the other leg being adapted to engage the platen-shift-frame, to hold the latter against movement when the device is in place, the ends of the legs being turned toward each other for guiding the spring to position.

5. A device, insertable into a typewriting machine, consisting of a spring folded upon itself to present two legs, each having in-reaching terminals, one of which legs is shaped to engage the main frame of the machine, and the other of which legs is offset to overlie a part of the platen-shift-frame, whereby, when the device is in position, the platen-shift-frame is held against upward movement.

6. In a typewriting machine, a main frame, a shift-frame within and somewhat spaced from the main frame, a device insertable into the machine between the two frames for engagement with both of the frames, to hold the shift-frame against movement with respect to the main frame, and a work-part receiver carried on said shift-frame to co-operate with said device.

7. In a typewriting machine, a main frame, a shift-frame within and somewhat spaced from the main frame, a device consisting of a spring having two legs, compressible toward each other, for entry into the machine between the two frames, one leg being adapted to engage the main frame, and the other leg being adapted to engage the shift-frame, to hold the latter against movement with respect to the main frame, and means adjustably carried by said shift-frame for locating work-parts.

8. In a typewriting machine, a main

frame having a side plate with a bead or offset thereon, a shift-frame within the main frame and somewhat spaced therefrom, and a device consisting of a spring having two legs, compressible toward one another, for insertion into the machine between the frames, one leg of the spring being engageable with the offset on the main frame, and the other leg of the spring being turned over a part of the shift-frame, when the device is in place, whereby the device is held down by the main frame, and, in turn, holds the shift-frame down against upward displacement.

9. In a typewriting machine, a main frame having a side plate with a bead or offset thereon, a shift-frame within the main frame and somewhat spaced therefrom, and a device consisting of a spring having two legs, compressible toward one another, for insertion into the machine between the frames, one leg of the spring being engageable with the offset on the main frame, and the other leg of the spring being turned over a part of the shift-frame, when the device is in place, whereby the device is held down by the main frame, and, in turn, holds the shift-frame down against upward displacement, a loop being formed in the spring where the legs are joined, to serve as a handle by means of which the device may be positioned and removed.

10. In a typewriting machine, type-bars pivoted to swing to printing position, a triple armed spring device insertable into the machine to engage the frame thereof, to engage and hold in printing position any type-bar which may have been moved to such position, and means removably engaged in the machine receptive of the type carried by said type-bars.

11. In a typewriting machine, type-bars pivoted to swing to printing position, an angular, compressible spring-device insertable into the machine to engage the frame thereof, and to engage and hold in printing position any type-bar which may have been moved to such position, and an adjustable anvil removably mounted in the machine on which the face of the type carried by said type-bars are received.

12. In a typewriting machine, type-bars pivoted to swing to printing position, a device consisting of a spring having two legs, one adapted to engage the frame of the machine, and the other to engage and hold in printing position any type-bar which may have been moved to such position, and an anvil adjustable in the machine to receive type carried by said type-bars when engaged by said device.

13. In a typewriting machine, a type-bar segment, type-bars pivotally mounted on the segment to be swung to printing position, a device insertable into the machine, with one

- part thereof in engagement with the frame of the machine, with another part thereof in engagement with the segment, and with another part thereof adapted to engage and hold in printing position any type-bar which may have been swung to such position, and means engageable in the machine receptive of type carried by said type-bars when in printing position. 5 65
- 10 14. In a typewriting machine, a type-segment, type-bars pivotally mounted on the segment to be swung to printing position, a device consisting of a spring having three legs offset from one another, one leg for engagement with the frame of the machine, another leg for engagement with the segment, and another leg engageable with and adapted to hold in printing position any type-bar which may have been swung to such position, and co-operative means engageable in the machine for adjusting the type carried by said type-bars when in printing position. 15 70
- 15 15. In a typewriting machine, a type-segment, type-bars pivotally mounted on the segment to be swung to printing position, a device consisting of a spring having three legs offset from one another, one leg for engagement with the frame of the machine, another leg for engagement with the segment, and another leg engageable with and adapted to hold in printing position any type-bar which may have been swung to such position, the device being compressible 20 75
- 20 30 for placement and removal, and an anvil receptive of type carried by said type-bars when swung into printing position. 80
- 25 16. In a typewriting machine, a platen-axle, an anvil placeable on the axle and adjustable thereon for positioning type-blocks to be set and soldered upon type-bars, a type-segment, type-bars pivotally mounted on the segment to be swung upward and rearward to the anvil, and a device consisting of a spring bent up at an intermediate 35 85 point thereof to form two legs, one of which legs is positionable against the front of the machine-frame, and the other of which is positionable under and against the segment; the latter leg having a third leg offset upward and rearward therefrom to engage and hold any type-bar which may have been swung to the anvil; the first-mentioned upward bend in the device serving as a handle for placement and removal thereof, and permitting compression of the device 90
- 35 17. In a typewriting machine, a platen-axle, an anvil placeable on the axle and adjustable thereon for positioning type-blocks to be set and soldered upon type-bars, a type-segment, type-bars pivotally mounted on the segment to be swung upward and rearward to the anvil, and a device consisting of a spring bent up at an intermediate point thereof to form two legs, one of which legs is positionable against the front of the machine-frame, and the other of which is positionable under and against the segment; the latter leg having a third leg offset upward and rearward therefrom to engage and hold any type-bar which may have been swung to the anvil. 105
- 40 18. In a typewriting machine, a platen-axle, an anvil placeable on the axle and adjustable thereon for positioning type-blocks to be set and soldered upon type-bars, a type-segment, type-bars pivotally mounted on the segment to be swung upward and rearward to the anvil, and a device consisting of a spring bent up at an intermediate point thereof to form two legs, one of which legs is positionable against the front of the machine-frame, and the other of which is positionable under and against the segment; the latter leg having a third leg offset upward and rearward therefrom to engage and hold any type-bar which may have been swung to the anvil; the first-mentioned upward bend in the device serving as a handle for placement and removal thereof. 110
- 45 19. In a typewriting machine having a rearwardly-directed bead or offset on the front plate thereof, a platen-axle, an anvil placeable on the axle and adjustable thereon for positioning type-blocks to be set and soldered upon type-bars, a type-segment, type-bars pivotally mounted on the segment to be swung upward and rearward to the anvil, and a device consisting of a spring bent up at an intermediate point thereof to form two legs, one of which legs is positionable against the front of the machine-frame, under the bead or offset thereon, and the other of which is positionable under and against the segment; the latter leg having a third leg offset upward and rearward therefrom to engage and hold any type-bar which may have been swung to the anvil. 115
- 50 20. A spring device, insertable into a typewriting machine, having integral means for engaging the frame of the machine, and other integral means for coincidentally engaging and holding any type-bar which may have been swung to printing position. 120
- 55 21. A device, insertable into a typewriting machine, consisting of a spring bent to have two legs, one leg being adapted to engage the frame of the machine, and the other leg to engage and hold any type-bar which may have been swung to printing position, said legs acting co-operatively and being of integral construction. 125
- 60 22. A device, insertable into a typewriting machine, consisting of a spring having three legs, one leg being engageable with the frame of the machine, another leg being engageable with the type-segment, and

a third being adapted to engage and hold any type-bar which may have been swung to printing position.

23. A device, insertable into a typewriting machine, consisting of a spring having three legs, one leg being engageable with the frame of the machine, another leg being engageable with the type-segment, and the third being adapted to engage and hold

any type-bar which may have been swung to printing position, said device being compressible for placement and removal, and being adapted to exert a spring-pressure upon any type-bar held thereby.
